UNITED STATES PATENT OFFICE.

FRED BASEDOW, OF CHICAGO, ILLINOIS.

FLASH-LAMP ATTACHMENT FOR ELECTRIC BATTERIES.

1,120,668.

Specification of Letters Patent. Patented Dec. 15, 1914.

Application filed June 4, 1914. Serial No. 842,937.

To all whom it may concern:

Be it known that I, FRED BASEDOW, a citizen of the United States, and a resident of the city of Chicago, in the county of Cook and State of Illinois, have invented a certain new and useful Improvement in Flash-Lamp Attachments for Electric Batteries; and I do hereby declare that the following description of my said invention, taken in connection with the accompanying sheet of drawings, forms a full, clear, and exact specification, which will enable others skilled in the art to which it appertains to make and use the same.

15 My invention relates generally to improvements in a flash lamp attachment for electric batteries, and it consists, essentially, in the novel and peculiar combination of parts and details of construction, as hereinafter first fully set forth and described and then pointed out in the claims.

In the sheet of drawings already referred to, which serves to illustrate more fully my said invention, Figure 1 is a longitudinal, vertical section of my device. Fig. 2 is a section in line 2—2 of Fig. 1. Fig. 3 is a longitudinal, vertical section on an enlarged scale of a fragment thereof. Fig. 4 is a like section disclosing a slight modification of construction. Fig. 5 is a vertical section through a detail of my flash lamp. Fig. 6 is an elevation of a fragment showing the invention as applied to a cylindrical dry cell or battery. Fig. 7 is a plan section thereof in line 7—7 of Fig. 6.

Like parts are indicated by corresponding symbols or characters of reference in all the figures of the drawings.

The object of my invention is the provision of a simple, handy, and efficient attachment which may be applied to any of the many standard electric batteries or dry cells now on the market, whereby the latter may, without change or modification, be converted into serviceable flash lamp for any purpose whatever. And correlated therewith, said invention contemplates means for oscillating the lamp portion thereof to any angle desired with respect

to the said battery so that light may be directed to obscure and inaccessible corners impossible to reach were the lamp or bulb fixedly attached to the source of electric energy.

In the drawing 10 indicates a typical type of rectangular dry cell and 11 the carbon element projecting exteriorly thereof. This element has a horizontally extending binding post 13 and nut 14 for attachment of connections, and the zinc element of said cell has an upstanding binding post and nut 12 and 12^a respectively. This construction is typical of a standard cell and my lighting attachment therefor comprises first an angular sheet metallic member 15, the horizontal leg 15^a of which is punctured for the reception of a tubular flanged insulating member 16, which member is adapted to embrace the binding post 12, the nut 12^a of which is intended to bear upon the flange of said insulation, there being a strip of insulating material 17 interposed between said horizontal leg 15^a of angular member 15 and the top of battery 10, so that the said member is thoroughly insulated from the binding post 12.

Angular member 15 is so fixed to binding post 12 that its vertical leg 15^b is disposed in a plane parallel to the plane of the carbon element 11, and said leg is punctured in alignment with binding post 13 for the reception of a bolt 18 over which is pivoted a leg 19 of an inverted U-shaped member 20, a like leg 21 of said member being similarly pivoted over said binding post 13 of the carbon element 11. The horizontal extensions 22 and 23 of U-shaped member 20 overlap, but are insulated from each other by a strip of insulating material 24, and, surrounding said horizontal extensions, is an internally threaded shell or socket 25 which is fixed to and in electrical contact with the horizontal extension 22 but insulated from extension 23 by insulation 26 as clearly seen in Figs. 3 and 4. Adapted to be threaded into socket 25 is an incandescent lamp or bulb 27, the contact 28 of which forms an electrical connection with horizontal extension

23 through an aperture 29 in insulation 26. It is to be understood that the exteriorly threaded shank 30 forms electrical contact with interiorly threaded shell 25. Fixed to 5 vertical leg 15^b of angular member 15 is a blade 31 of springy sheet metallic material, which blade when depressed by the finger of a hand forms electrical contact with binding post 12, thereby closing an electrical circuit and illuminating bulb 27. Fixed to the upper end of interiorly threaded shell or socket 25 is a reflector 32, which reflector is provided with a bead 33, at its open end for the reception of a lens 34, 10 a split wire ring 35 being snapped into said bead to retain the lens in position and to permit the removal thereof.

In Fig. 5 I disclose in detail a construction of the reflector which may be employed 20 in many instances. Within the reflector shell 32 is located a frosted glass reflector 32^a, which, with the lens 34, is maintained in position by wire 35 located in the bead 33 as hereinbefore described.

25 In Fig. 4 is indicated a slight modification of the switch for closing the electrical circuit. In this construction leg 21 is pivoted on binding post 13 as before, but is insulated therefrom by insulation 40. An aperture 41 is formed in carbon element 11 for the passage therethrough of a stud 42 fixed to a spring member 43 attached to the carbon element 11. By pressing inwardly 30 on said spring member 43 said stud contacts with leg 21, thereby forming electrical contact in a manner readily understood.

In Figs. 6 and 7 I illustrate another modification in the arrangement of the switch. A strip of insulating material 50 is fastened 40 to binding post 12 and the horizontal leg 15^a is fixed to said insulating material. A thumb nut 51 coacts with binding post 12. A sheet metallic spring blade 52 is pivotally mounted on insulating strip 50 by a rivet 45 53, which rivet is in electrical connection with leg 15^a. One face of the blade 52 is formed with a cut out 54, adapted to partially embrace thumb nut 51, to close the circuit and it is evident that when the blade 50 52 is oscillated away from said thumb nut, said circuit is open.

While it is intended that my invention be marketed independently of the batteries, 55 yet in a more elaborate contemplation, I may supply the battery as well, and with the same a suitable open topped battery casing A having a bail B and a fixed handle C.

60 While herein I have disclosed the preferred mode of practicing my invention and also several modifications thereof, I wish it understood that I may make such other changes and alterations as would suggest themselves to the skilled mechanic or permitted under the doctrine of equivalents.

Having thus fully described my invention I claim as new and desire to secure to myself by Letters Patent of the United States:

1. The combination with a battery having 70 binding posts extending therefrom, of an angular member fixed to one of said binding posts, a lamp carrying bracket pivoted to said angular member and the other of said binding posts, and a switch connected to 75 said angular member and adapted to contact with said binding post.

2. The combination with a battery having binding posts extending therefrom, of 80 an angular member fixed to one of said binding posts but insulated therefrom, an inverted U-shaped member pivoted to said angular member and to the other of said binding posts, and a lamp and reflector carried 85 thereby, said U-shaped member comprising two angular extensions insulated from each other, and an internally threaded lamp receiving socket connected to one of said extensions and insulated from the other.

90 3. The combination with a battery having binding posts extending therefrom, of an angular member fixed to one of said binding posts but insulated therefrom, a switch connected to said member, adapted to contact with said binding post, an inverted U-shaped member pivoted to said angular member and to the other of said binding posts, a lamp and reflector carried thereby, 95 said U-shaped member comprising two angular extensions insulated from each other, and an internally threaded lamp receiving socket connected to one of said extensions and insulated from the other.

100 4. The combination with a battery having binding posts extending therefrom of an insulating strip fixed to one of said binding posts, an upstanding non-insulating member fixed to said insulating strip, a switch on said strip connected to said non-insulated member and adapted to contact 105 with said binding post, a lamp carrying bracket pivoted to said upstanding member and the other of said binding posts, whereby said bracket may be oscillated in a vertical plane, and a lamp and reflector carried 110 by said bracket.

115 5. In combination, a lamp, a bracket supporting said lamp pivoted to one binding post of an electrical battery, a depending, pivoted member in connection with said bracket, fixed to another binding post of said battery, whereby oscillation of said bracket is provided for, there being electrical connection between said lamp and 120 said binding posts.

125 6. In combination, a lamp, a bracket supporting said lamp pivoted to one binding post of an electrical battery, a depending, pivoted member in connection with said 130

bracket, fixed to another bindig post of said battery, whereby oscillation of said bracket is provided for, there being electrical connection between said lamp and said binding posts, and means for breaking said electrical connection.

5 In testimony whereof I have hereunto set

my hand in the presence of two subscribing witnesses.

FRED BASEDOW.

In the presence of—

W. O. STARK,

C. S. STARK.
